(57) **CLAIM**

The ornamental design for a monitoring and diagnostic device for a switchgear, as shown and described.

DESCRIPTION

FIG. 1 illustrates an isometric front side view of a monitoring and diagnostic device for a switchgear.

FIG. 2 illustrates a front side view of the device shown in FIG. 1.

FIG. 3 illustrates a rear side view of the device shown in FIG. 1.

FIG. 4 illustrates a left side view of the device shown in FIG. 1.

FIG. 5 illustrates a right side view of the device shown in FIG. 1.

FIG. 6 illustrates a top side view of the device shown in FIG. 1; and,

FIG. 7 illustrates a bottom side view of the device shown in FIG. 1.

The broken lines in FIGS. 1, 2, 6, and 7 are for purposes of illustrating unclaimed portions of the device and form no part of the claimed design.
